UNITED STATES PATENT OFFICE.

CHARLES E. SMITH, OF PATERSON, NEW JERSEY.

NAPKIN-HOLDER.

No. 910,153.

Specification of Letters Patent.

Patented Jan. 19, 1909.

Application filed October 17, 1908. Serial No. 458,310.

To all whom it may concern:

Be it known that I, CHARLES E. SMITH, a citizen of the United States, residing in Paterson, Passaic county, New Jersey, have invented a certain new and useful Improvement in Napkin-Holders; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this my present invention is to provide, in a simple and compact mechanism, a means for holding napkins which shall be so constructed as to keep the napkins neatly folded in compact arrangement and protected against general exposure and handling, while permitting the free removal of the napkins only one at a time.

In carrying out my invention I have had in mind to adapt it particularly for use on restaurant counters and the like, and as adapted for this purpose it has been so shown in the accompanying drawing, being provided, for instance, with auxiliary holders for pepper, salt, vinegar and other condiment and similar receptacles; but it will be understood that the essential and novel features of the invention may be employed with or without such auxiliary holding means and not necessarily in the precise arrangement and construction of the parts herein described and shown for the purpose of illustration.

In the accompanying drawing, Figure 1 shows the invention as seen from the rear of a counter and mainly in vertical section; Fig. 2 is a back view, partly in section; Fig. 3 is a plan view of the top or cover; and, Fig. 4 is a horizontal sectional view just above the auxiliary holders.

a in the drawing designates a counter top. In the adaptation shown this has a vertical hole *b* formed therethrough to receive a tubular stem *c* projecting downwardly from and screwed into or otherwise rigidly secured in the bottom wall of a base *d*.

The base *d* has an opening *e*, preferably rectangular in cross-section, extending down into the same; said base will usually be cast metal. Into the opening *e* is fitted the lower end of a cross-sectionally rectangular holder *f*, also of metal, open at the top. A cover *g*

is secured to the holder *f* preferably in the manner to be described, so that it may be readily removed, if necessary, and this cover has a circular opening *h* formed centrally 60 therein.

A plunger *i* carried by a stem *j* is arranged to move vertically in the holder *f*, its stem extending down through the tubular stem *c* of the base *d*. The plunger is 65 normally forced upwardly preferably by the following mechanism: By means of a nut *k* screwed onto the lower protruding end of stem *c*, a plate *l* is clamped against the under side of the counter-top *a*; this plate has its 70 end portions turned downwardly and its extremities bent back, as at *m*, in embracing relation to bearing pins *n* on which are journaled peripherally grooved pulleys *o*, the extremities being bifurcated, as at *p* (Fig. 75 2), to receive the pulleys. A headed stud *q* projects from the lower end of the stem *j* and under this extends a cord or other flexible device *r* whose extremities extend over the pulleys *o* and are attached to eyes *s* on 80 a weight *t*, the weight being formed with a vertical hole *u* permitting the stem *j* to descend when the weight rises.

The napkins *v* are introduced, preferably through the opening *h*, being usually first 85 folded diametrically twice; they are placed in, a convenient number at a time, until the holder *f* is filled, and as they are introduced it will be understood that the plunger is 90 pressed down, causing the weight *t* to rise. The napkins, it will be observed, are held 95 against being ejected by the plunger under the action of the weight by the fact that they are not only of greater dimension than the opening *h* but are square, whereas the 95 hole *h* is circular. Only one napkin, and but a limited portion of that one, is therefore exposed at a time, and this, the topmost napkin, may be easily removed by grasping it at the opening *h* and withdrawing it. 100

It will be observed on reference to Fig. 1 that the cover *g* has the under or interior edge of its opening *h* cut away, as at *h'*. I have found in practice that where the edge 105 is not cut away in the manner shown or its equivalent it is not only more difficult to remove the napkins but the napkins are unduly creased and likely to become torn, especially if they are made of paper or the like. Furthermore, this cutting away of the interior edge of the opening *h* produces a bulging up of the topmost napkin so that a hold 110

on it can be effected in removing it; I have found that by this expedient only can the napkins be conveniently removed, since otherwise the top napkin is held so flat and in such close contact with the next subjacent napkin that a person is likely to remove the napkins two or more at a time, instead of one at a time, as intended.

Usually, the holder is filled in the manner above described; but, for the purpose of re-pairs, and also, under certain conditions in refilling the holder, the cover *g* may be removable. To this end the cover *g* has at one side a downwardly extending flange *w* provided with inwardly projecting lip *x*; this lip interlocks with an integral shoulder *y* formed on the corresponding outer side of the holder at the top thereof. Opposite the flange *w* the cover *g* has a downwardly projecting flange *z* formed with a groove *l* on the inside thereof. The flange *z* below the groove has on the inside thereof notches *2* leading to the groove; it also has a notch *3* to receive the downwardly projecting handle portion *4* of a bolt *5* arranged to slide between the flange and the holder *f* and provided with lugs *6* projecting into the groove. The bolt, in the locked position of the parts, bears upwardly against lugs *7* on the holder *f* and so long as the lugs *6* do not register with the notches *2* the cover is locked down; but on moving the bolt laterally the lugs *6* will register with the notches *2*, so that the cover will be released by the bolt and may be raised. By arranging the locking means for the cover in the manner described the outward neat appearance of the device is preserved, while the bolt is substantially concealed and protected against accidental or unauthorized actuation.

I prefer to attach auxiliary holders *8* and *9* to the holder *f* to receive salt and pepper shakers, vinegar cruets and the like, matches, tooth picks, etc.

Having thus fully described my invention, what I claim as new and desire to secure by Letters Patent is:

1. The combination of a container member having an opening in one wall thereof, means for pressing the articles inclosed in said

member normally toward said opening, comprising a plunger having a stem, a suitable support, a hollow stem projecting from the container member and penetrating the support, said plunger stem penetrating the hollow stem, and means on the hollow stem for securing the container member on the support, substantially as described.

2. The combination of a container member having an opening in one wall thereof, a plunger arranged in said container member and movable toward said opening, said plunger having a stem, a suitable support, a hollow stem carried by said container member and penetrating the support, said plunger stem penetrating the hollow stem, means, on the hollow stem, for securing the container to the support, a weight, a flexible device carrying the weight and engaging the plunger stem and guiding means for the flexible device arranged on the hollow stem, substantially as described.

3. The combination, with a suitable support, of a container member resting against the same, said member having an opening in the wall thereof opposite said support of less diameter in one dimension thereof than the corresponding inside dimension of said member, a plunger movable in said member toward and from the opening and having a stem, a weight, and a flexible device carrying the weight and engaging said stem and the support, substantially as described.

4. The combination of the holder member, an apertured cover member therefor, said cover and holder members having disengageable interlocking portions, and a bolt having projections and movable in one of said members parallel to the plane of their meeting faces, the other member having a notched portion engageable by the bolt, substantially as described.

In testimony, that I claim the foregoing, I have hereunto set my hand this 16th day of October, 1908.

C. E. SMITH.
